DESIGN FOR A COFFEE MAKER

Karl Schneider, Chicago, Ill., assignor to Sears, Roebuck and Co., Chicago, Ill., a corporation of New York

Application February 26, 1942, Serial No. 106,000

Term of patent 7 years

To all whom it may concern:

Be it known that I, Karl Schneider, a citizen of Germany, resident of the United States of America, having applied for first citizenship papers of the United States, residing at Chicago, in the county of Cook and State of Illinois, have invented a new, original, and ornamental Design for a Coffee Maker, of which the following is a specification, reference being had to the accompanying drawing, forming a part thereof.

I claim:

The ornamental design for a coffee maker, as shown.

KARL SCHNEIDER.
